COLLARBAND CONSTRUCTION FOR SHIRTS

Doak Norwood, Chicago, Ill.

Application June 22, 1943, Serial No. 491,792

6 Claims. (Cl. 2—141)

This invention relates to shirts of the type in which the collar is permanently attached to the shirt at the neckband.

One object of the invention is to provide fastening means for the two ends of the neckband which shall be more convenient to manipulate than the usual permanently mounted button at one end of the neck band, which cooperates with a buttonhole in the other end.

Another object of the invention is to provide a neckband for a shirt of the collar-attached type, arranged to utilize either a removable collar button or a sewed-on button permanently associated with the shirt.

A further object of the invention is to provide a shirt of the collar-attached type with a neckband having a connecting button carried by a flexible tape or tab secured to the band and foldable out of the position of use, together with provision for holding such tab at inactive position to permit the collar to be worn open with good appearance, or to utilize a removable collar button in a special buttonhole provided in the neckband for that purpose.

It is also an object of the invention to provide a new and improved shirt of the collar-attached type, having a button permanently associated with the neckband for connecting its ends together, but with provision for using alternative fastening means at will.

Other objects and advantages of the invention will appear from the following description taken in connection with the drawing, in which:

Fig. 1 is a fragmentary front elevational view of a shirt of the collar-attached type, which may be considered as a shirt embodying this invention, showing the same with the ends of the collar secured together, and with a necktie combined therewith.

Fig. 2 is a front elevational view showing the parts in the same position as Fig. 1, but with the necktie omitted, and indicating in dotted outline a portion of the tab by which the connecting button is carried.

Fig. 3 is a fragmentary front elevational view of a shirt embodying this invention, showing the collar arranged to be worn open at the throat.

Fig. 4 is a front elevation on a larger scale than the preceding figures, showing the neckband with a removable collar button positioned therein, and with the collar-carrying tab folded back out of service and secured to a special strap provided for that purpose.

Fig. 5 is a front view similar to Fig. 4, but showing the tab positioned ready for use in prep.

aration for buttoning the neckband in the manner indicated in Fig. 2.

Fig. 6 is a fragmentary front view, showing the neckband secured by a removable collar button, and showing the tab folded back out of service and tucked under the holding strap.

Fig. 7 is a front view similar to Fig. 6, showing the holding strap partially torn away, revealing the supplemental buttonhole thereunder.

Fig. 8 is a horizontal sectional detail taken substantially as indicated at line 8—8 on Fig. 4.

While there is shown and described herein certain specific structure embodying the invention, it will be manifest to those skilled in the art that various modifications and re-arrangements of the parts may be made without departing from the scope of the invention, and that the same is not limited to the particular form herein shown and described, except in so far as indicated by the appended claims.

Heretofore, a shirt of the collar-attached type has been made customarily with a button sewed onto one end of the neckband to cooperate with the buttonhole in the opposite end of the neckband for closing the collar, and this arrangement is fairly satisfactory when the collar is left soft and flexible. But when the collar is starched it is a matter of some difficulty to secure the ends of the neckband by entering the sewed-on button in the buttonhole and still avoid bending, folding or kinking the stiff collar in such a manner as will destroy its neat appearance. With the collar already starched, it is usually necessary to enter the necktie in the fold of the collar before buttoning the ends of the neckband, and the presence of the tie tends to complicate the difficulty. My invention, however, provides an arrangement which supplies the usual sewed-on button to be employed if the collar is left soft or unstarched, while permitting the use of a removable collar button which can be more easily manipulated for connecting the ends of the neckband if the collar is starched. Briefly, I provide each end of the neckband with a buttonhole so that a removable collar button may be employed therein; and I then provide a tab which overlies one of the buttonholes and carries a sewed-on button which can be engaged with the buttonhole at the other end of the neckband when the collar is not starched. As a result, the collar assumes a neat and smooth appearance at all times, whether it is worn soft or starched, and the time and temper of the wearer is conserved in the process of fastening the collar and adjusting the tie therein.

Fig. 1 illustrates the desired appearance of the collar 4, with a four-in-hand tie 2 worn in the usual manner. In Fig. 2, the tie being omitted, the points 3 and 4 of the collar are shown in their normal positions as secured by means of a button 5 carried on a special tab 6, which is a feature of this invention. The tab 6 is more clearly seen in Fig. 5, with its sewed-on button 6 positioned for engagement with the buttonhole 7 in the end portion 8 of the neckband. The portion 8 of the neckband is provided with a strap 10 which is positioned under the point 3 of the collar so as to be hidden thereby when the collar is in its normal position of use.

When the collar is starched it will be found preferable to employ a removable collar button, such as that shown at 11 in Fig. 4, and for that purpose the end portion 8 of the neckband is provided with a special buttonhole 12 to receive such collar button. The buttonhole 7 in the other end of the neckband may then be fitted over the button 11 for connecting the neckband in the usual manner. However, when the separate button 11 is employed it is desirable to have the tab 6 not only folded back to uncover the buttonhole 12, but preferably secured in that position in some manner. Accordingly, the strap 10 is made with a buttonhole 13 positioned to receive the button 5 when its tab 6 is folded back, as shown in Fig. 4. As thus shown and described, the collar is adapted for use either as a soft collar—in which case the sewed-on button 5 will be used as indicated in Figs. 2 and 5—or as a starched collar in which the ends of the neckband will be connected by means of the supplemental or separate collar button 11, shown in Fig. 4.

It may happen that in laundering a shirt of this type the button 5 may be torn off, or that upon weakening of the threads it may come off in use. If this happens, it is a simple matter to tuck the tab 6 under the strap 10, where it will be entirely out of the way, thus permitting the use of the separate collar button 11, even with an unstarched collar, as shown in Fig. 6.

Again, it may happen that instead of the button 5 coming loose and being lost from the tab 6, the strap 10 may be loosened from its stitching at one end or the other, as, for example, as shown in Fig. 7. To provide for this contingency, an emergency buttonhole 14 is formed in the neckband and is normally disposed under the strap 10; but if the strap should become loosened at one end it may be entirely removed, either forcibly or by cutting the remaining stitches by which it is held, and then the buttonhole 14 will serve to engage the button 5 when the tab 6 is folded back out of the position of use.

Thus, with the provision of a sewed-on button carried on a supplemental tab at one end of the neckband, I secure the usual comfort of a fairly flat connection between the two ends of the neckband which may be employed whenever the collar itself is left unstarched; and by the provision of an extra buttonhole 12 to receive a separate button 11, I provide for a convenient method of connecting the ends of the neckband when the collar is starched and therefore too stiff to be manipulated easily or safely without the danger of cracking or creasing it in a manner which would render it unsightly. Furthermore, the dual fastening means thus provided affords insurance against difficulty and embarrassment, which might otherwise arise from the loss of the usual sewed-on button which, with the standard construction,

leaves the shirt with no means of securing the ends of the neckband together.

Preferably, the neckband, and usually the remainder of the shirt will be made of pre-shrunk material, and with the tab 6 constructed of pre-shrunk, non-elastic material, the permanent fit, comfort and good appearance of the collar will be assured in the employment of the features of this invention. When the collar is worn open at the throat, as shown in Fig. 3, the presence of a buttonhole at each end of the neckband affords a symmetrical effect, and the tab 6 and strap 10 are entirely concealed under one wing of the collar.

I claim as my invention:

1. In a shirt of the collar attached type, a neckband having a buttonhole at each end, and a flexible tab secured to the outer face of the neckband at one end in position to overlie one of said buttonholes, together with a button permanently secured to said tab on its outer face in position to lie substantially over said buttonhole, and means to hold the free end of the tab folded back against the neckband away from said buttonhole when the button of the tab is out of service.

2. In a shirt of the collar attached type, a neckband having a buttonhole at each end, and a flexible tab secured to the outer face of the neckband at one end in position to overlie one of said buttonholes, together with a button permanently secured to said tab on its outer face in position to lie substantially over said buttonhole, and a strap secured by its ends against the outer face of the neckband forming a flat loop to receive and retain the free end of the tab when the tab is out of service.

3. In a shirt of the collar attached type, a neckband having a buttonhole at each end, and a flexible tab secured to the outer face of the neckband at one end in position to overlie one of said buttonholes, together with a button permanently secured to said tab on its outer face in position to lie substantially over said buttonhole, and a strap secured at its ends to the outer face of the neckband and having a buttonhole to receive the button of the tab when the tab is folded back away from the end of the neckband.

4. In a shirt of the collar attached type, a neckband having a buttonhole at each end, and a flexible tab secured to the outer face of the neckband at one end in position to overlie one of said buttonholes, together with a button permanently secured to said tab on its outer face in position to lie substantially over said buttonhole, said neckband having an additional buttonhole set back from the end of the neckband which carries the tab, and said additional buttonhole being positioned to receive the button of the tab when the latter is folded back out of service position.

5. In a shirt of the collar attached type, a neckband having a buttonhole at each end, and a flexible tab secured to the outer face of the neckband at one end in position to overlie one of said buttonholes, together with a button permanently secured to said tab on its outer face in position to lie substantially over said buttonhole, and a strap secured at its ends to the outer face of the neckband and having a buttonhole positioned to receive the button of the tab when the tab is folded back away from the end of the neckband, said neckband having an additional buttonhole directly under the buttonhole of the strap.

6. In a shirt of the collar attached type, a turned down collar including a neck band having a button hole at each end, and a flexible tab secured to the outer face of the neck band near one end in position to extend horizontally from under the collar and to overlie one of said button holes, together with a button permanently

secured to the free end of said tab on its outer face in position to lie substantially over said button hole, and means serving to hold said tab in an out-of-service position in which it is concealed between the neck band and the collar.

DOAK NORWOOD.
